UNITED STATES PATENT OFFICE.

MORRIS WUERPEL, OF ST. LOUIS, MISSOURI, ASSIGNOR TO WESTINGHOUSE AUTOMATIC AIR & STEAM COUPLER COMPANY, OF ST. LOUIS, MISSOURI, A CORPORATION OF ILLINOIS.

AUTOMATIC ELECTRIC COUPLING MECHANISM.

1,009,370.

Specification of Letters Patent. Patented Nov. 21, 1911.

Application filed April 17, 1907. Serial No. 368,696.

To all whom it may concern:

Be it known that I, MORRIS WUERPEL, a citizen of the United States, residing at St. Louis, Missouri, have invented certain new and useful Improvements in Automatic Electric Coupling Mechanisms, of which the following is a specification.

This invention has reference to automatic coupling apparatus for electric circuits and may be applied in connection with auxiliary coupler heads mounted below and attached to the ordinary M. C. B. coupler or other preferred type of coupler head, as for example in the case of the patent to Niederlander No. 827,988, or may be applied in conjunction with coupler heads which are arranged independently of the car coupler or other device for securing the cars together, the gathering mechanism for the heads, however, being in its main essential particulars substantially the same as that shown in said Niederlander patent and comprising the usual inclined ways and the spring device for bringing the heads into proper register and forcing the lateral engaging faces together, all substantially as has been heretofore known in the art.

The object of the present invention has particular reference to the arrangement of certain electrical contacts in a common insulating base carried upon such coupler head, and to the provision of an improved form of contact connection whereby a better connection will be obtained when the coupler heads are locked together, and whereby the parts will be less liable to derangement or damage in ordinary service, or as a result of the coming together of the coupler heads through the action of the gathering mechanism.

This improvement may be used as indicated in the accompanying drawings, in conjunction with a gathering device and heads having air-hose or other fluid pressure connections, or it may be used if preferred, in conjunction with heads in which such fluid pressure connections are not employed, but in order to make the entire application of the improvement clear the same has been shown in conjunction with coupler heads employing such fluid pressure connection.

Referring to the accompanying drawing, it will be seen that Figure 1 indicates, in elevation a view of the engaging face of a coupler embodying my improvement; Fig. 1^a is a section on the line A—A of Fig. 1; Fig. 2 is a rear view in elevation, that is a view from outside looking inward toward the center of the car, while Fig. 3 is an end view looking inward toward the center of the car; Fig. 4 is a sectional view indicating the arrangement of the box in which the terminal wires are incased and the main or bus bar connection of the group of electrical contacts, while Fig. 5 is a sectional view indicating the arrangement of the female members of the group of electrical contact connections, and Fig. 6 is a sectional view indicating the arrangement of the male members adapted to register with the connections shown in Fig. 5. Fig. 7 is a sectional view taken on the line B—B of Fig. 1.

Referring now more particularly to Figs. 1, 2 and 3 it will be seen that I have therein indicated a coupler head marked 7 carrying a couple of fluid pressure openings 8 which may be of usual construction and provided with the ordinary form of gathering means comprising primarily the inclined faces 9 and the spring 10 constructed to work in substantially similar manner to those heretofore known in the art, and below the coupler head 7 there is extended a projecting band or yoke 11 within which is an insulating plate 12 carrying a plurality of electrical contacts of which 13 indicates the bus bar contact and the terminals or the other contacts which are for the various different circuit lines are indicated in two rows, the female portions being marked 14 and the male portions or projecting tongues 15, the tongues and the sockets which receive the same being made of elongated shape substantially as indicated on Fig. 1, the two parts being arranged in two vertical columns in position so that it will not matter which end of the car comes opposite the adjoining car they will always register and couple correctly.

It will be seen on examining Figs. 1 and 3 that the coupler heads are provided with a shoulder indicated at 16, which holds the

gaskets around the openings 8, and also the electrical tongues or projections 15 out of engagement until the coupler heads are in substantially correct position or register, 5 when the springs at the back of the heads will force them together after the shoulders 16 on the opposite heads have passed each other so as to permit such lateral motion of the two heads. This lateral motion then 10 will permit the tongues to drop into the recesses 14, forming a sliding and clean connection, while the bus bar contact 13 by virtue of its spring shape as indicated in Fig. 4 will be pressed back into the recess marked 15 17, and form a good electrical contact.

It will be further observed that the slotted piece of insulating material indicated generally by the reference character 12 is composed of two parts 18 and 19 for convenience of manufacture, and these two parts are anchored in the socket or base part 20 which at its rear has an opening covered by a plate 21, which latter can be readily removed to secure access to the interior of the 25 terminal box 22 in which are the terminals of the various cables which connect with the bus bar connection 13 and the various projections 15 and socket pieces 14.

The operation of my improvement is as follows: The two ears coming together the gathering mechanism operates in the usual manner to direct the two coupler heads 7 into their proper relative position, the shoulder projections 16 on each of the heads serving to 30 force the two heads a little distance apart to protect the projections 15 against damage, until the two heads are in proper position for contact, when these shoulders 16 will pass each other and the spring 10 will 35 drive the two heads together, into the coupled position, as shown in Fig. 7, the same motion being accompanied with a slight rubbing motion of the contact faces 15 within their sockets 14, both because of the lateral motion due to the spring 10 and the slight play back and forth of the two coupler heads after the shoulders 16 pass each other. The socket parts 14 are preferably 40 arranged so as to have the side faces 23 somewhat elastic, in order to secure better contact, provision for such elastic operation being arranged by the relief afforded by the clearance space 24 indicated in Fig. 5.

It will be seen by examination of Fig. 5 45 that the use of the two parts 18 and 19 in the construction of the insulating plate facilitates the insertion of the contact terminals and the holding of the same in place by means of the flanges 25 shown in said 50 Fig. 5, corresponding constructions to which are provided on the other contact members. The cables being all brought into the terminal pieces with the insulation reaching up to the insulating blocks, it is obvious that by the 55 arrangement shown there is nothing ex-

posed which is in open connection with the electric circuit except the interior faces of the female parts and the projecting tongues 15 and the bus bar connection 13, all of the rest being thoroughly insulated and protected against interference of any kind. 70

Having thus described my invention and illustrated its use, what I claim as new and desire to secure by Letters Patent, is the following:

1. An automatic electric coupler comprising in combination a coupler head, a socket therein containing an insulating base plate, a plurality of contact connections arranged in said base plate in pairs arranged in a vertical plane, one male and one female in each pair, and the pairs arranged with both members on substantially the same horizontal plane. 80

2. An automatic electric coupler device comprising in combination a base plate, a head carrying said base plate, automatic means for coupling said head, and contact connections provided in said base plate in a vertical row of pairs, said pairs being arranged on horizontal planes to register with corresponding pairs of a companion coupling member, substantially as described. 90

3. An automatic electric coupling device comprising in combination a coupler head, automatic means for coupling said head, a base plate carrying a plurality of contact connections, said contact connections comprising a vertical row of male contacts, and an adjacent vertical row of female contacts, 100 each pair of contacts being on the same horizontal plane, substantially as described. 95

4. An automatic electric coupling device comprising in combination a coupler head, a base plate, said base plate containing a plurality of electrical contact connections adapted to make lateral engagement with corresponding electrical contact connections of a coöperating coupling member, said contact connections being arranged in lines vertically and in corresponding horizontal planes, substantially as described. 105 110

5. An automatic electric coupler comprising in combination a coupler head, a socket therein containing a longitudinally arranged insulating base plate, a pair of contact connections in said base plate, and the contacts arranged with both members on substantially the same horizontal plane. 115

6. An automatic electric coupler comprising in combination a coupler head, a socket therein containing a longitudinally arranged insulating base plate, knife blade connections in said base plate, one male and one female, and the contacts arranged with both members on substantially the same horizontal plane. 120 125

7. In an automatic electric coupler, the combination with counterpart heads adapted to couple upon relative longitudinal move- 130

ment thereof, of an insulating base plate carried by each head and male and female connections carried by said base plate, said connections being arranged in vertical rows 5 and in pairs, comprising a male and a female connection located in a substantially horizontal plane.

In testimony whereof I have hereunto signed my name in the presence of the two subscribed witnesses.

MORRIS WUERPEL.
